UNITED STATES PATENT OFFICE

104,076

DESIGN FOR A RADIATOR COVER

See Thie Liem, The Hague, Netherlands

Application January 14, 1935, Serial No. 54,844
In Switzerland December 13, 1934

Term of patent 14 years

To all whom it may concern:

Be it known that I, See Thie Liem, a subject of the Queen of the Netherlands, residing at The Hague, in the Province of Zuid-Holland, in the Kingdom of the Netherlands, have invented a new, original, and ornamental Design for a Radiator Cover, of which the following is a specification, reference being had to the accompanying drawing, forming part thereof:—

I claim:

The ornamental design for a radiator cover, as shown.

SEE THIE LIEM.
